UNITED STATES PATENT OFFICE.

JOHN WEBB, OF CHICAGO, ILLINOIS.

BOX-FOLDING MACHINE.

SPECIFICATION forming part of Letters Patent No. 623,586, dated April 25, 1899.

Application filed November 3, 1897. Serial No. 657,241. (No model.)

To all whom it may concern:

Be it known that I, JOHN WEBB, of Chicago, in the county of Cook and State of Illinois, have invented certain new and useful Improvements in Box-Folding Machines; and I do hereby declare that the following is a full, clear, and exact description thereof, reference being had to the accompanying drawings, and to the letters of reference marked thereon, which form a part of this specification.

This invention relates to box folding and pasting machinery, and is designed in its completed form to fold and paste the end flaps of a tubular box-blank which has the flaps at one or both ends unfolded. Said machine is provided with a suitable form adapted to receive the tubular blank and to automatically fold or bend the flaps upon each other, the last one folded of which has been previously or simultaneously therewith supplied with a suitable adhesive material and is provided with means for exerting pressure upon the said flap, which will be applied a sufficient length of time to permit the paste or gum to set. The tubular blank, with one end thus closed, is then automatically stripped from the machine.

A second feature of the invention contemplates means for receiving a filled box with one end closed in the manner described, but with the other end open, and means for closing said open end of the box by folding the opposite and intermediate flaps of said open end automatically, the last one folded being supplied with a suitable paste, and providing means for holding the said flap thus folded in position until the paste thereon has set.

The invention is herein illustrated in a machine consisting of an open oblong rectangular frame carrying over sprocket-wheels at each end thereof an endless carrier, to which are attached flap-folding devices, and to the frame of which are attached the various mechanisms for actuating and controlling said flap-folding devices as they pass successively from one end of the machine to the other. As herein shown, said carrier consists of two endless chains, one on each side of the machine, made up of relatively long links, said links being joined together by means of transversely-arranged slats. In this machine it will be noted that the devices for closing the

front end of the box-blank are attached to said carrier at one side of the machine, while the flap-folding devices for finally closing the box are attached to the carrier on the opposite side of the machine. It will of course be understood that these two operations are not required to be conducted in the same machine, although this is desirable. Likewise the device for folding and holding the last or gummed flap on each end of the box is shown in connection with the means for automatically actuating the flap-closer; but this feature of the invention being separable is also shown on a separate figure without any automatic device for actuating the flap-closer, and inasmuch as a plurality of such separate devices for holding the gummed flap in position until the gum or paste is set may be used to carry it where the folding of the flaps is performed by hand by cheap labor.

With these general statements as to the object of the invention I now proceed to describe the drawings, which illustrate an operative machine embodying my invention, but respecting many of the details of construction of which machine I do not desire to be limited, except as hereinafter specifically claimed.

Figure 1 is a side elevation of the right-hand side of a machine embodying one form of my invention. Fig. 2 is a transverse view of the same, enlarged, showing simply the frame, the links of the endless chains, the tracks for the same, and other details hereinafter to be mentioned. Fig. 3 is a plan view of one of the links of the chain, enlarged, showing the means connecting said link with the ends of the adjacent links. Fig. 4 is a side view of the same. Fig. 5 is a perspective view of the flap holding and setting devices. Fig. 6 is a vertical sectional detail thereof, enlarged. Fig. 7 is a transverse vertical sectional view of a portion of the machine, enlarged, showing right and left hand folding devices in elevation, the right-hand device being that which performs the first operation above referred to and the left-hand device being that which closes the end of the box-blank after it has been filled with any desired material. Fig. 8 is a side elevation, enlarged, of the flap-folding devices for performing said first operation. (Shown on the lower lap of the carrier.) Fig. 9 is a perspective view, enlarged,

of the side-flap folding and holding plate, together with the arms secured thereto for engagement with a cam, whereby the plate is automatically dropped. Fig. 10 is a vertical 5 sectional view of the folding device shown in Fig. 8. Fig. 11 is a horizontal sectional view of the same, taken upon line 11 11 of Fig. 10. Fig. 12 is a plan view of the receptacle in which the folded box is placed, together with 10 the end and one side of the flap-closing device. Fig. 13 is a vertical sectional view of the same, taken upon line 13 13 of Fig. 12. Fig. 14 is a vertical sectional view of the same, taken upon line 14 14 of Fig. 12, and showing 15 also in section the folding and setting plate. Fig. 15 is a side elevation, enlarged, of the folding and flap-setting device as a whole for closing the filled box.

First referring to Figs. 5 and 9 of the drawings, I will describe the operation of the flap folding and setting device. A is a tubular box-blank open at each end and provided with oppositely-arranged flaps a , attached to the narrow side walls of the box, and intermediate flaps $a' a^2$, attached to the wider side walls thereof, as indicated in Fig. 9, which are adapted to be folded upon each other to form the closed end walls of the box. For convenience said flaps $a a'$ will hereinafter 20 be designated as the "end" flaps and the flaps $a' a^2$ as the "side" flaps. A' is a block or form of any suitable size, over which said tubular blank may be placed, so that the edges a^3 of one set of flaps $a a' a^2$ will rest upon and 25 be supported by a suitable projection or table A^2 , the block A' being of such height from the table or shoulder A^2 as to form at its upper end a support or shoulder over which the opposite set of flaps $a' a^2$ of the box-blank A 30 may be folded. The blank A being placed by hand upon the block A', the operator will first fold the end flaps a toward each other upon the top of the block A' and will then fold successively the two side flaps $a' a^2$, and the 35 last one of which will be supplied upon the under side thereof with paste, by which it will be secured to the subjacent side flap. This operation by hand requires only a very short time; but the side flap last folded 40 must be held in position a relatively long time in order that the paste carried thereby will set. With my improved device, Fig. 5, the operator will now move the holding-plate B in position over the top of the side flap a^2 45 and will then pass to the next block A' and repeat the operation, the holding-plate B being thus automatically held in its position by means of the mechanism now to be described.

Conveniently located with respect to the 50 block A' are two side or upright members of a frame B' and a transverse member b. To the transverse member b are secured tension, flat, or leaf springs b', which springs engage at their upper or free ends one margin of the 55 holding-plate B. As shown in Figs. 5 and 6, antifriction-rollers b³ are secured to the plate B, which the ends of the springs actually en-

gage; but it is obvious that the said antifriction-rollers b' may be omitted, if desirable. The plate B is pivotally secured at b³ to the 70 vertical frame members B', and the rear margin of said plate, that which engages the springs b', is bent upwardly to a plane above said point of pivot, as shown in Fig. 6. From this construction it will be manifest that when 75 the plate B is in a horizontal position, as shown in said figure, or in a plane below its pivotal connection b³, the location of the springs b' and their point of engagement with the upturned margin of said plate or with said 80 antifriction-rollers b², above said pivotal connection b³, said plate B will be firmly held by the springs b' upon the flap a². The plate will likewise be held in a raised position when the antifriction-rollers b² have passed below 85 the plane of said pivotal connection of the plate. In Fig. 6 the plate is shown as having two parts, that lettered B and that lettered B², the two parts being secured together by bolts and nuts, as shown at b⁴. This construction is employed for the purpose of removing the portion lettered B and securing in its place a plate of different size or shape and which will be desirable whenever the block 90 A' is removed and one of a different size or 95 shape substituted therefor. This block A' may be secured to the shoulder or table A² by a thumb-screw a⁴ or otherwise.

In the form of flap folding and setting device shown in Fig. 9 the plate B is shown as 100 constructed of one piece, and to said plate are secured arms B³, to which an antifriction-roller b⁵ is secured. The arms B³ form a lever in connection with the plate B and its pivotal connection b³, and the roller b⁵ may engage a suitable cam or curved track, whereby the lever will be moved at a desired interval, and thus the plate B may be actuated to fold the flap, while the springs b' will retain the plate B in position until the latter is either 105 raised by hand or the cam or track causes the lever B³ to move in the other direction.

It is obvious from the foregoing description of the mechanism shown in Figs. 5, 6, and 9 that this one feature of the invention may be 110 incorporated in a machine, as shown in the other figures of the drawings, or may be separately employed, and in the latter case it will be of great advantage even where the operations of folding the two ends and the side 115 flaps of each end of a box are performed by hand. There may be a plurality of such end folding and setting plates B separately located upon some suitable bench or table or they may be located upon some revolving table. In the latter case the operator should place a box-blank upon the block or form A', fold it and paste it, drop the plate B down upon it, and proceed to the next box or form. By the time 120 the table moves around so that this particular box is again in front of the operator the paste or glue will be set and the operator will then raise the plate B by hand, remove the box-blank, and place another in position.

In the machine which I have illustrated in the other figures of the drawings I have provided mechanism for not only automatically lowering the plate B when desired, holding it in position an appropriate length of time and then automatically raising it, but also mechanism for raising the box-blank or dropping it from the block A' after the paste is set and the plate has been thus automatically raised from the box.

Before proceeding with further explanation of the mechanism for automatically folding the side and end flaps in what is herein termed the "first" operation on the box-blank I will describe the machine as a whole.

C C are vertical standards of the frame, secured at their lower ends to a suitable transverse base-plate C', one at each end, by bolts c or in any other convenient manner, and 20 suitably connected together at necessary points by angle-irons c', extending lengthwise of the machine, and transverse angle-irons c'', extending across the machine. At one end of the frame is mounted in suitable brackets a 25 rotatable shaft C², upon which shaft is mounted two laterally-separated sprocket-wheels C³, one on each side of the machine, and a driving-pulley C⁴. Motion is communicated to the shaft C², through said driving-pulley C⁴, 30 from any suitable source of power, through the medium of a driving-belt c³ or otherwise. At the other end of the machine a similar shaft C⁵ supports two laterally-separated sprocket-wheels C³, and over the sprocket-wheels at each end of the machine an endless carrier, designated as a whole by the letter D, 35 is trained. Said belt as herein shown consists generally of two endless chains located upon laterally-opposite sides of the machine 40 and transverse slats D³, secured at their opposite ends to the links of said chains. Said chain is made up of a plurality of relatively long links, to each of which two transverse slats are secured. It is desirable that the 45 journal-box c⁴, in which the shaft C⁵ is mounted, be adjustably secured to the frame in order that said shaft may be adjusted for the purpose of taking up or giving any desired slack in the said carrier D. As one means of 50 affording such adjustability I have shown the journal-box c⁴ as having a sliding engagement with upper and lower bars c⁵, which extend between the two uprights C C at this end of the machine, and as being provided with a 55 screw-threaded bolt c⁶, which passes through a suitable aperture in the upright C and is engaged from the outside thereof by a suitable nut c⁷. It will be manifest that upon turning the nut c⁷ the screw-threaded bolt c⁶ 60 may be drawn through the aperture in the upright C, thus drawing the journal-box c⁴ toward said upright, carrying with it the shaft and sprocket-wheels carried thereon and thereby tightening the carrier D.

65 The links of the carrier D are shown in detail in Figs. 3 and 4, each link comprising two side members d and a spreader-spool d'

at each end thereof, a pivot or connecting pin d² passing through each of said spools, and antifriction-rollers d⁸ on the outer ends 70 of said pin outside of the side members d. The teeth c⁸ of the sprocket-wheels C³ pass between the said members d of each link and engage the spreader-spool d', which will be rotatively mounted upon the pins d². Each 75 lap of each belt D travels upon a track, the lower track of the right-hand belt being shown at D', Figs. 1 and 2, while the upper track is shown at D², Fig. 1. The latter track consists simply of an angle-iron suitably secured 80 at each end to a transverse angle-iron d⁴, which are in turn secured to the uprights C at the opposite ends of the machine. The lower track D' consists of two angle-irons secured together to form an elongated channel-bar, the open side of which is directed inwardly and within which the belt of the carrier D is mounted. Said bars are mounted in opposite sides of the machine and secured therein by being riveted to angle-plates d⁵, 85 mounted upon the upright members C at each end of the machine. The opposite links of the laterally-separated endless chains D are secured from movement with relation to each other by means of the transversely-arranged 90 bars D³, which bars are secured at their ends to inwardly-projecting lugs d⁷ upon the innermost member of the side bars d of each link by means of bolts d⁶, as more clearly shown in Fig. 7. There are two of said horizontally-arranged bars D³ for each pair of 95 links, and it is to these bars that I prefer to secure a portion of the flap folding and setting mechanism.

Referring now to the flap folding and setting mechanism shown at the right-hand side of the machine, or that seen in elevation in Fig. 1, it will be seen by an inspection of Figs. 8 and 10 that the block A' over which the box-blank A is placed is not a solid block 100 and that it is surrounded in the lower part thereof by the opposite members of a vertically-movable yoke E, which is hereinafter termed a "stripper." Said stripper consists of two side members, which engage opposite 105 sides of the block A' and are flared outwardly at their upper ends, as shown at e, which upwardly-flaring end forms a shoulder upon which the lower margins a³ of the flaps a a' a², when the box-blank A is placed over the block 110 A', may rest, as clearly shown in dotted lines in Fig. 10. After the blank is thus located upon the block or form A' the end flaps a a are folded together by means of folding-fingers G, as seen more clearly in Figs. 7 and 8. 115 Said folding-fingers are made in the form of a V-shaped plate and are pivoted at their lower or narrow ends to standards G', which are mounted upon cross-bars f², secured in any suitable manner to the transverse slats 120 D³, said fingers G extending at its upper or wider end adjacent to the upper end of the block A'. Said fingers G are actuated by means of vertically-extending links G², which

are pivoted at their upper ends to integral lugs mounted on said arms and are attached at their lower ends to a vertically-movable plate G³. Said plate is provided with a depending bracket g upon the lower side thereof, carrying an antifriction-wheel g', which is adapted to engage and travel upon a track G⁴, which is herein shown as secured by means of angle-irons or brackets g² to the main frame. Said plate G³ is guided in its vertical movement by means of two guide-rods g³, which depend from the lower side of the plate f² in parallel relation and which rods pass through suitable apertured bosses constituting bearings g⁴ on said plate G³. Pins g⁵ upon the guide-rods g³ limit the downward movement of the plate G³, and springs G⁵, interposed between said cross-bar f² and plate G³ and preferably surrounding the guide-rods 20 g³, serve to hold the plate G³ normally in its lowermost position, as shown in Fig. 8, and the fingers retracted from the upper end of the former block. An inclined portion g⁶ of the track G⁴ acts as a cam when the roller-wheel g', moving in the direction indicated by the arrow in Fig. 8, passes over it, thereby raising said plates G³ vertically through the medium of the bracket g, which acts in turn through the links G² to swing the upper ends 25 of the pivotally-mounted fingers or folders G toward each other and to thereby tuck or fold the flaps a into their proper position upon the upper end of the block A'. After the flaps a a have thus been folded upon each other 30 the side flap a' is then folded over upon said end flaps by the folder or finger F. Said folder or finger F has the same form as the fingers G described, and is provided at its lower end with an apertured hub f, by means 35 of which it is pivoted to a standard F', mounted upon the cross-bar f², said finger being secured to the standard by means of a pivot-pin f⁴, as clearly shown in Fig. 7. Said finger is provided at its lower end with an outwardly-extending lug f', to which is secured, by means of a pivot-pin f⁵, the upper end of a vertically-reciprocating actuating-rod, which rod is provided at its lower end with an antifriction-roller f⁶. Said rod F² passes 40 through a suitable bearing f⁷ in the plate f², and frame F' is normally held in its lowermost position or that shown in Figs. 7 and 8 by means of a spiral spring f⁸ surrounding said rod and impinging at one end against 45 the plate f² and at its other end against a shoulder formed by a pin f⁹ upon said rod F². At the proper time in the movement of the device as a whole lengthwise of the machine the roller f⁶ strikes an inclined or cam surface f¹⁰ or a short track f¹¹ and rides over the same. The inclination of the cam-surface is such as to cause an upward or vertical movement of the rod F², which in turn moves the outer end of the finger F toward the box 50 A, the inwardly-projecting portion f¹² thereof striking the flap a' and folding it over upon the flaps a, which have been previously folded 55

upon said block, as described. After said flaps a a' have been thus folded, the under side of the flap a² is then supplied with paste 70 or other suitable adhesive material and the folding and setting plate B is then moved down upon the flap a² by reason of the wheel b⁵ upon the outer ends of the arms B³ riding upwardly upon the cam-surface B⁴ of the track B⁵. Said track B⁵ is suitably mounted upon angle-irons b⁶ b⁷, which in turn are secured to the cross-bar b⁸ and a depending bar b⁹, forming the parts of the frame.

In the completed machine the relation of 80 the cam-surface g⁶ to the cam-surface f¹⁰, Fig. 8, is such that in point of time the end flaps a will be folded first, and just as the finger F is moving over to fold the flap a' the wheel g' will roll down an inclined or cam surface 85 g⁷, and thus release the fingers G as they are moving away. The flat or straight main portion F¹¹ of the track, which is engaged by the antifriction-roller f⁶ of the actuating-rod F², holds the parts in such position that the finger F will be held firmly upon the folded flap a' until just before the folding and setting plate B is actuated. At this time the antifriction-roller f⁶ of said rod F² strikes a downwardly-inclined surface f¹³ of the track, which 95 permits the spring f⁸ to retract the rod F² and withdraw the finger F.

It will be noted by reason of the bolt connections the frames F' and G' may be removed from the cross-bars f², and frames of 100 different heights may span them, thus making it possible to adjust this machine to different sizes of boxes. The flap-setting plate B, however, need not be removed entirely from the machine, since I have made provision for adjusting the side frame-pieces B', to which the plate B is pivoted. I provide upon the cross-bars D³ of each plate vertical standards B⁶, which form guides for the standards B', the latter being provided at their 105 upper and lower ends with outwardly-projecting apertured flanges b⁷, through the apertures of which the said guide-posts B⁶ pass. A connecting-plate b⁸ extends between the upper ends of the guide-rods B⁶, through 110 which plate the upper ends of said rods pass and to which they are secured by the nuts b⁹. An intermediate rod B⁷ is secured at its lower end to the cross-bar B³, and at its upper end it is secured to the plate b⁸ by a nut b¹⁰. Projecting rearwardly from the plate b is a block 115 b¹¹, provided with a vertical aperture which is engaged by the rod B⁷ and through which said rod slides. b¹² is a set-screw passing through said block b¹¹ and having its end impinging or bearing against the guide-rod B⁷. By this means the vertical adjustment of the flap folding and setting plate B is accomplished and regulated as desired.

From the foregoing description it will be 130 manifest that the operator, sitting on the right-hand side of the machine, facing the side illustrated in Fig. 1 of the drawings, with a number of tubular box-blanks A conven-

iently at hand, places the said blanks one by one over the block or forms A' as each link of the chain D, traveling in the direction indicated by the arrows, Fig. 1, passes before her. It will be understood that each link of the chain D is provided with a complete set of flap folding and setting devices, above referred to, and of which but two only are illustrated in position in Fig. 1. After the flap-setting plate B has been turned down upon the flap a² by reason of the fact that the wheel b³ runs over the upwardly-inclined track or cam B⁴ the said holder B is retained in its position upon the flap by the action of the springs b during the further travel of the carrier D, notwithstanding the fact that said roller b³ leaves the track B⁵ at the point indicated at B⁸. When first placed upon the block A', the box is in an upright position and is supported above the lower lap of the carrier D; but it will be noted that the position of the box becomes inverted when the particular link carrying the same becomes a member of the upper lap of the carrier, the box itself then projecting downwardly. When the lever B³, carrying the roller-wheel b³, approaches the left-hand end of the track B⁵, the said roller enters the same at the point marked B⁹, and almost immediately thereafter the flap-holder B is raised by reason of the action of the cam or downwardly-inclined surface B¹⁰ of the track B⁵. Immediately upon being released from the pressure of the holding-flap B the blank A is stripped from the block A' by the stripper E. The lower end of the stripper E is provided with two wheels E' E², the former being preferably a grooved wheel. The wheel E' travels upon the track E³, extending lengthwise of the machine at the lower side thereof, and said track E³ is provided with an upwardly-inclined or cam surface e', the inclination being so arranged with reference to the downwardly-inclined portion B¹⁰ of the track B⁵ that the stripper E will be caused to move upwardly at or immediately after the plate B is raised. As before stated, the stripper E moves vertically upward upon the outside of the block A'. A set of rollers e² on either side of the stripper E serve as a guide therefor, the rollers being rotatably mounted in suitable brackets e³, depending from the cross-bar f², one on either side of the stripper E. The stripper E having been moved vertically upward by the action of the upwardly-inclined cam-surface of the track e' for the purpose of pushing the box-blank, with its one folded end, upwardly off the block A', it is necessary to immediately move it downwardly to its former position in order that a second blank may be placed upon the block A. This downward movement is accomplished by means of an auxiliary track or downwardly-inclined cam-surface E⁴, which is held in position slightly above and at one side of the track E³ by means of suitable brackets e³, as more clearly shown in Figs. 1 and 7. The roller-wheel E² upon the lower end of the strip

E engages the under side of this downwardly-inclined cam-surface E⁴ and by its connection with the stripper E moves said stripper to its normal lower position. 70

The opposite or left-hand side of the machine is provided with a plurality of devices for folding the flaps on the box-blank after the latter has been filled, each of said devices being secured to the opposite ends of the cross-slats D³ of the carrier to the folders just described, as more clearly shown in Fig. 7. The mechanism for folding the last flap and holding it in position until after the paste or glue has set being precisely the same in construction and operation as that hereinabove described for the right-hand-side folder, the description will not be repeated, and the same reference-letters are used to designate the corresponding parts. The same general idea is also employed in the mechanism used for folding the two end flaps a a and for folding the first side flap a' as it is used on the right-hand side of the machine; but the details of the mechanism varying slightly will now be described. 85

H is a hollow frame or receptacle provided at its lower end with outwardly-projecting flanges h, which rest upon and are secured to the cross-slats D³. In this receptacle H is placed the box A, with its closed end downward and filled with whatever material is to be placed within the box. The length of this receptacle H is such that the flaps will project entirely above the upper edge thereof, as plainly indicated in dotted lines in Fig. 13. The receptacle H is provided with a false or movable bottom H', supported upon two rods h', which pass through a suitable bearing in the bottom of the receptacle and unite at their lower ends and carry a small grooved wheel h². The latter rests upon a track H² on the left-hand side of the machine opposite the track E³, previously referred to. This track H² is provided with suitable cam-surfaces, so that at a proper time the grooved wheel or roller h² passes over the same, and thereby causes the movable bottom H' to move upwardly in the receptacle H and push out the box A from said receptacle. The lower ends of the rods h' are provided with a laterally-extending roller-wheel H³, which works against the under side of a cam-surface or track h³, which latter is supported upon a bracket h⁴. These parts h³, h⁴, and H³ act precisely in the same manner as do the parts E², E⁴, and e³, heretofore described, and therefore they will not be further illustrated or described. 115

The means for operating the fingers which fold the end flap a of the box (see Figs. 13 and 15) comprise links I, connected at their lower ends with a vertically-movable plate I', which latter is actuated by a track G⁴ on the left-hand side of the machine, corresponding with the track G⁴, heretofore referred to, said plate I having depending arms i', which carry a roller i in engagement with said track 125 130

G⁴. The flanges *h* are provided, further, with vertically-depend ing guide-rods *i*², which pass through suitable apertures in said plate I'. In the lower ends of said guide-rods are mounted transverse stop-pins *i*³. Said pins *i*³ limit the downward movement of the plate I' upon the guide-rods *i*². Springs I², preferably surrounding said guide-rods *i*², engage at their upper ends the under side of the plate *h* and at their lower ends the upper surface of the plate I', which springs tend to hold the plate I' to its lowermost or normal position after the roller-wheel *h*² has passed over the upwardly-inclined cam-surface *g*⁶ of the cam-track G⁴. The upper ends of said links I are pivotally engaged to the short arms of bell-crank levers I³, which levers are in turn pivotally secured to suitably upwardly-extending side brackets I⁴ of the receptacle II. The brackets *i*⁴ are provided with downwardly-inclined grooves *i*⁵, said grooves being formed by the turning over of the edges *e*⁶ of the inclined portions of the brackets *i*⁴, and in said grooves are located the folder-fingers I⁴. Said fingers I⁴ are centrally slotted or apertured at *i*⁷ and are provided with transverse pins or arms *i*⁸ in said slot or aperture *i*⁷. The long arm of the bell-crank lever I³ is bifurcated, as shown at *i*⁹. The two parts of the end of the lever enter the slot *i*⁷, one on either side of the pin *i*⁸. It will be seen from this construction that when the plate I' is moved upwardly it will move the links I in the same direction, which will in turn actuate the bell-crank lever I³, so that the long arm thereof will describe the arc of a circle in the direction of the box-blank, and that this movement will cause fingers I⁴ to move downwardly and inwardly in their respective guide-slots *i*⁵ until their lower ends engage and fold the end flaps *a* of the box. It will also be noted that upon the return or downward movement of the plate I' and the links I the bell-crank levers will cause the fingers I⁴ to move in the opposite direction and resume their normal upper position, as indicated in Fig. 13. The side flap *a*' is folded by a finger J, acting in the same manner as the finger F, but instead of being hinged to a standard, as is the latter construction, it is hinged to the front side wall of the receptacle II, as indicated in Figs. 12 and 14. Said finger J is provided with two laterally-separated lugs *j* and a pin *j*². J' designates an actuating-rod which is provided in its upper end with a slot *j*', by which it is engaged with the pin *j*². The lower end of the rod J carries a roller-wheel *j*³, which roller corresponds with the roller *f*⁶ of the folder first described and is actuated by a track with inclined cam-surfaces on the left-hand side of the machine corresponding with the track *f*¹¹ on the right-hand side of the machine, previously explained.

65 The box-form A, having one of its ends closed by the devices on the right-hand side of the machine, as described, is filled and

placed within the receptacle H on the left-hand side of the machine. The end flaps *a*' are then folded over by the fingers I⁴, the side flap *a*' folded down upon the flap *a* by the finger J, and, finally, the flap *a*², which has been previously supplied on its under side with paste, is folded over the flap *a*² and held in position by the folding and setting plate B. 75

As before stated, it is manifest that there are many details of construction in the foregoing description of a machine embodying my invention which are not absolutely essential to the carrying out of the invention and which may be modified in various ways without departing from the essence or spirit of the invention, and all such modifications I claim within the scope of my invention. 80

I claim as my invention— 85

1. A box-folding machine embracing a traveling carrier, and means for folding the last flap of the box and retaining it in position comprising a form or block mounted on said carrier, a pivoted retaining plate or arm and means engaging said plate in a manner to hold the same either in its raised or lowered position. 90

2. A box-folding machine embracing a traveling carrier, a form or block mounted on said carrier, a pivoted flap-holding plate or arm, means for automatically raising said plate from or lowering it upon the form and means acting to hold said plate either in its raised or lowered position. 95

3. A box-folding machine embracing a form for holding the box-blank, a standard mounted adjacent to said form, a pivoted folding-plate mounted on said standard, a tension device for holding said plate either in its upper or lower position, and means for adjusting the relation of the pivoted plate to the box-holding block. 105

4. A box-folding machine embracing a traveling carrier, a blank-holding block or form mounted on said carrier, a standard mounted adjacent to said block, a folding-plate pivoted to said standard, a tension device for holding said plate either in its upper or lower position, and means for automatically raising or lowering said plate. 110

5. A box-folding machine embracing a traveling carrier, a blank-holding block mounted on said carrier, a standard mounted adjacent to said block, a plate pivoted to said standard, a tension device on said standard engaging said pivoted plate and adapted to hold the latter either in its upper or lower position, and means for automatically raising or lowering said plate, comprising a cam-surface or track mounted rigidly adjacent to said form, and an arm projecting from said plate and adapted to engage said cam-surface or track. 120

6. A box - folding machine comprising a main frame, a traveling carrier in said frame, a form or block mounted on said carrier, a flap folding and retaining plate pivotally secured upon said carrier adjacent to the block, a track provided with an inclined or cam sur-

face, rigidly secured to said main frame, an arm secured to said folding and retaining plate, and engaging said track.

7. A box - folding machine comprising a main frame, a traveling carrier mounted on ways in said frame, means for actuating said carrier, a form or block mounted upon said carrier, a pivotal flap folding and retaining plate adjustably secured to said carrier adjacent to the block, a track provided with inclined or cam surfaces rigidly secured to said main frame, an arm secured to said pivoted plate and a roller-wheel on the end of said arm and engaging said track.

15 8. A box - folding machine comprising a main frame, a traveling carrier, a form or block mounted on said carrier, a flap folding and retaining plate pivoted on said carrier adjacent to said block to swing in a vertical plane, and adapted to engage the block when in its lower position, a tension device engaging said pivoted plate and adapted to hold the latter either in its upper or lower position, a track rigid with said frame and provided 20 on one end thereof with a cam-surface adapted to engage and move said plate in its lower position upon the block and provided on its opposite end with a cam-surface adapted to raise the plate from the block.

25 9. A box - folding machine comprising a main frame, a traveling carrier mounted on ways on said frame, means for actuating said carrier, a form or block mounted on said carrier, a flap folding and retaining plate pivotally secured upon the carrier adjacent to said block to swing in a vertical plane and adapted to engage the upper end of said block when in its lower position, a tension device engaging said pivoted plate to hold the latter either 30 in its upper or lower position, an actuating-arm attached to said plate and provided on its outer end with an antifriction-roller, a track rigidly mounted on said frame and provided on one end thereof with a cam-surface and 35 adapted to engage said antifriction-roller to move said plate in its lower position, and provided on its opposite end with a cam-surface adapted to raise the plate from the block.

40 10. A box-folding machine, embracing a blank - holding block or form, a standard mounted adjacent to said block, a plate pivoted to said standard to swing in a vertical plane, the rear edge of said plate being formed to extend above the plane of the pivot of said 45 plate, a tension device engaging said rear edge of the plate whereby said plate will be held either in its lower or upper position, and means on the frame adapted to engage said plate to automatically raise or lower the same in the 50 movement of the carrier in the frame.

45 11. A box - folding machine embracing a blank - holding block or form, a standard mounted adjacent to said block, a plate pivoted upon said standard to swing in a vertical 60 plane, the rear edge of said plate being formed to extend above the plane of the pivot of the plate, an antifriction - roller upon said rear

edge of the plate, a leaf-spring affixed at one end to the standard and engaging at its opposite end said antifriction-roller, and means 70 on the frame for automatically raising and lowering said plate in the movement of the carrier in the frame.

12. A box - folding machine comprising a main frame, a traveling carrier mounted on ways in said frame, a form or block mounted on said carrier, a frame or standard affixed to the carrier adjacent to said block comprising parallel guide-rods, and a cross-head extending between the same, means for adjusting said cross-head longitudinally of the rods, a folding and retaining plate pivotally mounted on the cross-head to swing in a vertical plane, and engaging when in its lower position the upper end of said frame, a tension device mounted on said cross - head to hold said plate either in its upper or lower position, and means on the frame for automatically raising and lowering said plate in the movement of the carrier in the frame.

15 13. A box - folding machine comprising a main frame, a traveling carrier mounted in ways in said frame, a form or block on said carrier, a frame or standard affixed to the carrier adjacent to the block comprising parallel guide-rods, a cross-head mounted to have longitudinal movement thereon, a locking-rod affixed to said carrier and engaging said cross-head, means for locking said cross-head to said rod, a spring-pressed folding and retaining plate mounted on said cross-head to swing in a vertical plane, and means on the frame for automatically raising and lowering said plate in the movement of the carrier in the frame.

20 14. A box - folding machine, comprising a main frame, a sprocket - wheel rotatively mounted in each end thereof, means for imparting motion to one of said wheels, an endless traveling carrier passing over said wheels, a form or blank holder mounted upon said carrier, a flap-folding device mounted also upon said carrier adjacent to the block or form comprising a side-flap folder, two end-flap folders and a second side-flap folding and retaining 25 plate, arms projecting from each of said folders, tracks permanently secured to said main frame with which the ends of said arms engage, and cam-surfaces upon said tracks adapted to actuate said several arms.

30 15. A box-folding machine comprising a main frame, a wheel rotatively mounted in each end thereof, means for imparting motion to one of said wheels, an endless traveling carrier passing over said wheels, a form or blank holder mounted upon said carrier, flap-folding devices secured also to said carrier, comprising a side-flap folder, two end-flap folders and a second side-flap folding and retaining plate, arms projecting from each of said folders, tracks permanently attached to said main frame with which the ends of said arms engage, cam-surfaces upon said tracks adapted to actuate said several 35

arms, and a stripping device comprising a vertically-movable part engaging said form or blank holder, an arm projecting from said movable part, and a track in engagement with the lower end of said arm, said track being secured to the main frame and provided at a suitable point with a cam-surface adapted to actuate said arm of the stripping device.

16. A box - folding machine embracing means for folding two opposite flaps upon one end of a box-blank comprising a form or block, folding-fingers adapted to engage flaps connected to two opposite side walls of the blank, actuating-arms secured at one end thereof to a universal plate or bar and at their opposite ends oppositely connected with said folding-fingers, a track secured to the main frame of the machine and provided with a cam-surface adapted to engage and actuate said universal plate or bar and means for moving said folding mechanism with respect to said track.

17. A box - folding machine, embracing means for folding two opposite flaps upon one end of a box-blank, comprising a form or block, folding-fingers adapted to engage the flaps connected to two opposite side walls of the blank, actuating-arms secured at one end thereof to a vertically-movable universal plate and at their opposite ends pivotally connected with said folding-fingers, a depending bracket on said vertically-movable plate, an antifriction-roller in the lower end thereof, a track on the main frame of the machine and provided with a cam-surface adapted to engage said antifriction-roller and to thereby actuate said universal plate and the folding-fingers connected therewith, and means for moving said folding mechanism with respect to the track.

18. A box - folding machine, embracing means for folding two opposite flaps upon one end of a box-blank, comprising a form or block, folding-fingers adapted to engage the flaps connected to the two opposite side walls of said blank, actuating-arms secured at one end thereof to a universal plate and at their opposite ends pivotally connected with said folding-fingers, a track secured to the main frame of the machine and provided with a cam-surface adapted to engage and actuate said universal plate, folding-fingers connected therewith, and means for restoring said plate to its normal position when disengaged from said cam-surface, and means for moving said folding mechanism with respect to the track.

19. A box - folding machine embracing means for folding two opposite flaps upon one end of a box-blank, comprising a form or block, folding-fingers adapted to engage the flaps connected to two opposite walls of the blank, actuating-arms secured at one end thereof to a vertically - movable universal plate and at their other ends pivotally connected with said folding-fingers, a depending bracket on said plate, an antifriction-roller mounted in said bracket, a movable carrier to which said folding mechanism is attached,

a track secured to the main frame of the machine and provided with a cam-surface adapted to engage said antifriction-roller and actuate said plate as the device passes forward over the track, and a spring engaging said plate to restore the same to its normal position upon the track when said roller is disengaged from the cam-surface of the track. 75

20. A box - folding machine embracing means for folding the side flaps of one end of a box comprising pivoted folding-fingers, vertically-movable rods pivotally secured thereto, a movable carrier supporting and moving said folding mechanism, a stationary track on the main frame provided with a cam - surface adapted to actuate said rod and means for restoring said folding-fingers after being actuated by the cam-surface. 85

21. A box - folding machine comprising a main frame, an endless traveling carrier mounted therein, a form mounted on said carrier over which a tubular blank may be mounted, means for folding the end flaps of said blank over said form, a stripper for removing said blank from the form comprising a vertically - reciprocating frame, embracing said form and engaging at its upper end the lower end of said blank, and means on the frame 95 for actuating said stripper to remove the blank from the frame.

22. A box-folding machine comprising a main frame, an endless traveling carrier mounted therein, a form mounted on said carrier over which a tubular blank may be placed, means for folding the end flaps of said blank over said form, a stripper for removing said blank from the form comprising a vertically-reciprocating frame, embracing said form and 105 engaging at its upper end the lower end of said blank, means on the frame for actuating said stripper to remove the blank from the form, and means for restoring said stripper to its normal or lower position. 110

23. A box-folding machine comprising a main frame, an endless traveling carrier mounted therein, a form on said carrier over which a tubular box-blank may be mounted, means for folding the end flaps of said blank 115 over the said form, a stripper for removing the blank from the form comprising a reciprocating frame embracing said form and engaging at its upper end the lower end of the blank, a track mounted on the main frame 120 and provided with an upwardly-inclined cam-surface adapted to engage said stripper to move the same vertically upon the form and a downwardly-inclined cam-surface upon said track adapted to engage said stripper to restore it to its normal or lowermost position. 125

24. A box-folding machine comprising a main frame, an endless traveling carrier mounted therein, a form on said carrier over which a tubular box-blank may be mounted, 130 means for folding the end flaps of said blank over said form, a stripper for removing said blank from the form comprising a vertically-reciprocating frame embracing said form and

engaging at its upper end the lower end of the blank, an antifriction-roller on the lower end of said stripper, a track on the frame provided with an upwardly-inclined cam-surface 5 adapted to engage said roller to move the stripper vertically upon the frame, a downwardly-inclined cam-surface on said track and a second roller mounted on said stripper and adapted to engage the under side of said 10 last-mentioned cam-surface.

25. A box-folding machine comprising a main frame, an endless traveling carrier mounted therein, a form on said carrier over which a tubular blank may be mounted, means 15 for folding the end flaps of said blank over said form, a stripper for removing said blank from the form, comprising a vertically-reciprocating frame normally embracing the lower end of said form and engaging at its upper 20 end the lower end of the blank, guide-rollers between said carrier and stripper, and means on the frame for actuating said stripper to remove the blank from the form.

26. A box-folding machine comprising a main frame, an endless traveling carrier therein, a hollow receptacle mounted on said carrier and adapted to receive a box-blank, folding-fingers movably mounted on said receptacle and adapted to move inwardly to fold the 30 flaps connected to the two opposite sides of the blank, and operative connections between said fingers and the machine-frame for actuating the same.

27. A box-folding machine comprising a main frame, an endless traveling carrier therein, a hollow receptacle mounted on said carrier adapted to receive a box-blank, brackets on the opposite sides of the upper end of said receptacle provided with oppositely and inwardly inclined guide-grooves, folding-fingers mounted in said grooves and adapted to move inwardly to engage the flaps connected to two opposite sides of the box-blank, and operative connection between said fingers and the machine-frame for actuating said fingers. 45

28. A box-folding machine comprising a main frame, an endless carrier therein, a hollow receptacle mounted on said carrier adapted to receive a box-blank, brackets on the opposite sides of the upper end of said receptacle provided with oppositely and inwardly inclined guide-grooves, folding-fingers mounted in said grooves, and means for moving said fingers inwardly to fold the flaps connected 50 with two opposite side walls of the box-blank, comprising a bell-crank lever pivotally connected with said fingers and operative connection between said levers and the machine-frame.

60 29. A box-folding machine comprising a main frame, an endless traveling carrier mounted therein, means for actuating said carrier, a hollow receptacle mounted on said carrier and adapted to receive a box-blank, means for folding the flaps connected with two opposite side walls of said blank comprising oppositely and inwardly inclined folding 65

fingers movably mounted on said receptacle, bell-crank levers pivoted to said receptacle and connected at one end with said fingers, 70 and operative connections between the opposite ends of said levers and the machine-frame.

30. A box-folding machine comprising a main frame, an endless carrier mounted therein, means for actuating said carrier, a hollow receptacle mounted on said carrier and adapted to receive a box-blank, means for folding the flaps connected with two opposite side walls of said blank comprising oppositely and inwardly inclined folding-fingers movable in 80 said receptacle, bell-crank levers pivoted to said receptacle and pivotally connected at one end with said fingers, actuating-rods pivotally connected at one end thereof with said levers and at their opposite ends with a vertically-movable plate, a stationary track on said frame provided with an upwardly-inclined cam-surface adapted to engage said vertically-movable plate. 85

31. A box-folding machine comprising a main frame, an endless traveling carrier mounted therein, means for actuating said carrier, a hollow receptacle mounted on said carrier and adapted to receive a box-blank, means for folding the flaps connected with two 90 opposite side walls of said blank comprising oppositely and inwardly inclined folding-fingers movable in said receptacle, bell-crank levers pivoted to said receptacle and pivotally connected at one end with said fingers, actuating-rods pivotally connected at one end thereof with said levers and at their opposite ends with a vertically-movable plate, a stationary track on said frame provided with upwardly-inclined cam-surface adapted to 95 engage said vertically-movable plate, and means for restoring said plate to its normal or lowermost position when disengaged from said cam-surface. 100

32. A box-folding machine comprising a main frame provided in its opposite ends with rotative pulleys, a carrier trained over said pulleys and adapted to travel in ways mounted in said frame between the pulleys, a box-blank form mounted on said carrier, means for simultaneously folding the flaps connected with two opposite side walls together and upon the form, means for folding one of the intermediate flaps upon said first-mentioned flaps, and means for folding a fourth intermediate flap upon the form, to the under side of which paste has been applied and for holding said flap in place until the paste thereon becomes set. 115 120

33. A box-folding machine comprising a main frame provided in each end with two laterally-separated sprocket-wheels, a carrier trained over said wheels comprising two endless sprocket-belts connected together by transverse slats and adapted to travel on ways mounted on said frame between said sprocket-wheels, a box-blank form mounted on one of said transverse slats of the carrier, means for simultaneously folding the flaps connected 130

with two opposite side walls of the blank together and upon the form, means for folding one of the intermediate flaps upon said first-mentioned flaps, and means for folding and retaining a fourth intermediate flap upon the flaps previously folded.

34. A box-folding machine comprising a main frame, an endless traveling carrier therein, a flap-folding device mounted on said carrier comprising a form or blank holder, folding-fingers upon opposite sides thereof to fold the flaps connected with two opposite side walls of the blank, a stationary track on the frame provided with a cam-surface, operative connections between said cam-surface and said folding-fingers, a third finger for folding one of the intermediate flaps of the blank, a second stationary track located in advance of said first-mentioned track with respect to the movement of said carrier, provided with a cam-surface, operative connections between said cam-surface and said last-mentioned folding-finger, a plate pivotally mounted adjacent to the frame for folding

and retaining a second intermediate flap of the blank, and a third stationary track provided adjacent to one end of the machine with means for closing said plate upon the form to fold said second intermediate flap and at the opposite end of the machine with means for raising said plate, and means for stripping said blank from the form.

35. A box-folding mechanism comprising a blank-holding block or form, a pivoted retaining plate or arm, the rear edge of which is formed to extend outside of the plane of the pivot of said plate and a tension device engaging said rear edge of the plate and acting to hold said plate either in its open or closed position.

In testimony that I claim the foregoing as my invention I affix my signature, in presence of two witnesses, this 29th day of October, A. D. 1897.

JOHN WEBB.
